UNITED STATES PATENT OFFICE

JULIUS BERNSTEIN, OF CHICAGO, ILLINOIS, ASSIGNOR TO B. & B. SHOE COMPANY, OF CHICAGO, ILLINOIS, A CORPORATION OF ILLINOIS

DESIGN FOR A CARTON OR SIMILAR CONTAINER

Application filed December 19, 1931. Serial No. 42,137. Term of patent 3½ years.

To all whom it may concern:

Be it known that I, JULIUS BERNSTEIN, a citizen of the United States, and resident of Chicago, in the county of Cook and State of Illinois, have invented a new, original, and ornamental Design for a Carton or Similar Container, of which the following is a specification, reference being had to the accompanying drawings, forming a part thereof.

Figure 1 is a perspective view of a carton showing my new design, the decoration being omitted because of the size of the figure, and being shown on a large scale in the other figures;

I claim:

The ornamental design for a carton or similar container, substantially as shown and described.

Signed at Chicago, in the county of Cook and State of Illinois, this 25th day of November, A. D. 1931.

JULIUS BERNSTEIN.
